(57) **CLAIM**

The ornamental design for a video camera assembly, as shown and described.

DESCRIPTION

FIG. 1 is a front perspective view from above of the video camera assembly showing the new design;

FIG. 2 is a front perspective view from below of the video camera assembly showing the new design;

FIG. 3 is a front view in elevation of the video camera assembly showing the new design;

FIG. 4 is a back view in elevation of the video camera assembly showing the new design;

FIG. 5 is a left side view in elevation of the video camera assembly showing the new design;

FIG. 6 is a right side view in elevation of the video camera assembly showing the new design;

FIG. 7 is a top view in plan of the video camera assembly showing the new design;

FIG. 8 is a bottom view in plan of the video camera assembly showing the new design;

FIG. 9 is a front perspective view from above of the video camera assembly with showing the new design with its privacy cover removed;

FIG. 10 is a right side perspective view from below the video camera assembly showing the new design with its base support pivoted downward; and,

FIG. 11 is a front perspective view from above showing the video camera assembly mounted on a television unit.

(Continued)

The broken lines showing unclaimed portions of the video camera assembly or its unclaimed environment in use form no part of the claimed design.
